(21) Appl. No.: **29/582,593**

(57) **CLAIM**

(22) Filed: **Oct. 28, 2016**

The ornamental design for a combined transaction product
and carrier sleeve, as shown and described.

DESCRIPTION

(51) LOC (11) Cl. 03-01
(52) U.S. Cl.
USPC D3/300; D3/247
(58) Field of Classification Search
USPC D3/247, 249–253, 300
CPC A45C 1/06; A45C 3/08
See application file for complete search history.

FIG. 1 is a top, front perspective view of a combined
transaction product and carrier sleeve showing a our new
design in a first configuration;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a top, front perspective view of the combined
transaction product and carrier sleeve of FIG. 1 showing a
our new design in a second configuration;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

In the drawings, the broken lines depict unclaimed subject
matter only and form no part of the claimed design.

1 Claim, 6 Drawing Sheets
